Henry S. Brewington
by J. Dom, Cleary, Attorney

UNITED STATES PATENT OFFICE.

HENRY S. BREWINGTON, OF BALTIMORE, MARYLAND.

BOTTLE-STOPPER.

SPECIFICATION forming part of Letters Patent No. 703,528, dated July 1, 1902.

Application filed December 9, 1901. Serial No. 85,157. (No model.)

To all whom it may concern:

Be it known that I, HENRY S. BREWINGTON, a citizen of the United States, residing at Baltimore, in the State of Maryland, have invented certain new and useful Improvements in Bottle-Stoppers; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to bottle-stoppers of the class known as bottle seals or caps.

The primary object of the invention is to provide a seal or cap which may be easily removed by the use of a suitable opener.

A further object of the invention is to provide a seal or cap so constructed as to contain a cork packing which extends well over the outer edge of the mouth of a bottle to protect the edge and prevent the chipping of the glass by the contact therewith of an opener in removing the cap.

A still further object is to provide the upper portion of the depending cylindrical portion of the cap with corrugations disposed vertically, or approximately so, to insure the retention therein of the cork packing.

With these several ends in view the invention consists in the improved construction of bottle-cap hereinafter described in connection with the accompanying drawings, and particularly pointed out in the appended claims.

In the drawings, Figure 1 is a side elevation of the cap before its application to a bottle. Fig. 2 is a central vertical section of the same. Fig. 3 is a vertical section showing the cap applied to a bottle-neck. Figs. 4, 5, and 6 are side elevations of modifications of the invention, and Fig. 7 is a horizontal section of Fig. 1.

Referring to Figs. 1, 2, and 3, the numeral 45 1 designates a bottle-neck formed with an annular external shoulder 2 and an annular groove 3.

The cap comprises a disk 4 and an annular flange bent to form an enlarged head 5 and 50 a depending vertical portion 6. Within the enlarged head 5 is inclosed a packing 7, of cork or other suitable material, which rests

upon the rim of the bottle-mouth, as shown in Fig. 3, and is of sufficient diameter to extend beyond the outer edge of the bottle-mouth to protect said edge from contact with the opener and to form, in conjunction with the head 5, an annular rib above the bottle-mouth adapted to be engaged by an opener.

The peripheral edge of the head 5 is formed 60 with a series of corrugations 8, which are preferably disposed vertically in parallel relation, but may be slightly inclined or curved.

The peripheral edge of the cork packing enters the depressions formed on the inner 65 surface of the head 5, and the packing is thus held securely in position within the cap.

In Figs. 4, 5, and 6 I have shown modified embodiments of the invention in which the flange 9 of the cap is not circumferentially 70 enlarged, but has its upper portion corrugated to secure the cork packing. In Fig. 4 the corrugations are in the form of parallel vertical ribs, in Fig. 5 the corrugations are of elliptical form, and in Fig. 6 they are shown 75 parallel, but slightly inclined.

The construction described provides a seal which protects the edge of the bottle-mouth and prevents chipping thereof by the pressure or contact of the opener and affords an 80 annular rib above the bottle-mouth for the engagement of an opener. The device also insures a secure attachment of the cork packing within the cap.

I claim—

1. The combination with a bottle-neck formed with an external annular shoulder, of a seal comprising a disk and a depending flange the lower edge of which is compressed below the shoulder while its upper portion is 90 annularly enlarged to project beyond the mouth of the bottle to present a projecting head above the bottle-mouth adapted to be engaged by an opener, and a packing below the disk, the peripheral edge of which fits 95 within the annular head and projects over the bottle-mouth.

2. The combination with a bottle-neck formed with an external annular shoulder, of a seal comprising a disk and a depending 100 flange bent to form an annular head which is corrugated and projects beyond the bottle-mouth to present a surface adapted to be engaged by an opener, and a packing below the

disk the peripheral edge of which is engaged and secured by the corrugations of the projecting head.

3. The combination with a bottle-neck formed with an external annular shoulder, of a seal comprising a disk, and a flange bent to form an annular corrugated head, and a depending portion adapted to be compressed under said shoulder to secure the seal in place, and a packing having its periphery fitted within the head of the cap and extending beyond the outer edge of the bottle-mouth, said annular head projecting above the bottle-mouth and beyond the outer edge thereof, and adapted to be engaged by an opener.

4. A bottle-cap comprising a disk, and a depending flange annularly enlarged to provide a projecting head, formed with vertical corrugations, and a packing within the cap having its peripheral edge engaging said corrugations, the lower portion of the flange being plain to adapt it to engage an annular shoulder on a bottle-neck by spinning or compressing said lower portion of the flange. 20

In testimony whereof I affix my signature 25 in presence of two witnesses.

HENRY S. BREWINGTON.
